REFRIGERATING APPARATUS

Lawrence A. Philipp, Detroit, Mich., assignor to
 Nash-Kelvinator Corporation, Detroit, Mich., a
 corporation of Maryland

Application August 25, 1938, Serial No. 226,814

5 Claims. (Cl. 62—115)

This invention relates to an improvement in refrigerating apparatus, and more particularly to refrigerant cooled sealed units, wherein the motor and compressor are contained in a hermetically sealed casing or housing.

The invention consists in providing a suitable condenser substantially enclosing the side walls of a sealed casing, so that at least three side walls of the sealed casing are enclosed by the 10 condenser, and providing a fan with a shroud which is attached to the free ends of the condenser. Upon the operation of the fan air will be drawn through the condenser causing the air to absorb the heat emanating from the walls of 15 the sealed casing and thereby cooling the motor-compressor unit.

The invention further consists in providing a jacket, preferably, composed of a coil of tubing, having thermal contact with the sealed casing. 20 by entirely encircling the side wall or walls thereof. Connected to the ends of the tubing is a secondary condenser disposed above the coil of tubing and over the top of the sealed casing. The jacket or tubing is charged with a quantity 25 of any suitable fluid capable of absorbing heat in such a system, for example, sulphur dioxide, or other refrigerant agents, and even water may be employed. The liquid refrigerant in the tubing or jacket upon boiling, due to the extraction of heat from the sealed casing, will pass 30 into the secondary condenser in the form of vapor, where it will condense and return to the tubing or jacket.

The invention consists of certain novel features of construction and combinations of parts 35 which will be hereinafter described and set forth in the appended claims.

In the accompanying drawings:

Figure 1 is a view partly in elevation and partly 40 in vertical section illustrating the invention;

Figure 2 is a top plan view with the secondary condenser removed;

Figure 3 is a plan view of the secondary condenser; and

Figure 4 is a plan view of a modified form of condenser that may be substituted for the main condenser.

In the drawings 10 represents a dome-shaped shell or casing, which is open at one end, and 45 having at its open end an outwardly extending flange 11. Mounted within the shell 10 and preferably vertically disposed therein is a unit, consisting of an electric motor 17 and a compressor 18. The upper portion of the motor 17 engages 50 a shoulder 19 formed on the inner wall of the

shell 10, and an annular ring 20 engages the lower end of the motor 17 and a cover or button plate 21 for supporting the motor 17 and compressor 18 as a unit within the shell. The bottom or cover plate 21 is attached to the flange 11 of the shell 5 by bolts 22—22 for closing the shell 10 and for hermetically sealing the motor-compressor unit within the shell 10.

The vaporized refrigerant is returned from an evaporator 12 of a refrigerating system to the 10 shell 10, by a conduit 23 connected by a suitable coupling 24 to the cover 21. The refrigerant then passes through another conduit 25 into the interior of the shell 10. The refrigerant in shell 10 passes through compressor intake conduit 26, 15 which has its inlet end in open communication with conduit 25, and this vaporized refrigerant is compressed by the compressor 18. The compressed refrigerant is conducted from the compressor by conduits 27 and 28 to a condenser 29. 20 The conduits 27 and 28 are connected by a suitable coupling 30 carried by the cover 21 for conducting the refrigerant from the compressor 18 to the condenser 29. The refrigerant vapor will be condensed in the condenser 29, and the liquid 25 refrigerant will be conducted by a conduit 31 to a suitable receiver and float mechanism 13 before being delivered to the evaporator 12 by means of a conduit 32 which connects the receiver with the 30 evaporator.

The condenser 29, as shown in Figures 1 and 2 is preferably made in three sections, or of a construction to encompass, at least, three sides or walls of the casing 10 containing the motor-compressor unit. Two of the sections 33, 34 are 35 connected to the intermediate section 35 by suitable couplings 36—36. The refrigerant delivered from the compressor, is conducted to the condenser section 33 by the conduit 28 which is connected thereto by a coupling 37.

The refrigerant vapor on entering the condenser section 33 will flow therefrom into condenser section 35 and then into condenser section 34 from where it will be discharged through conduit 31 to the high side float chamber or receiver 13 the refrigerant being condensed during its passage through said sections. Each of the condenser sections 29 is composed of sinuous tubes 38 which are rigidly secured between end plates 39—39. The tubes 38 of the condenser 50 sections are provided with suitable fins 40 forming heat dissipating surfaces.

A shroud 41 is connected to the free ends of the condenser sections 33 and 34 and extends 55 across the remaining or fourth side of the sealed

casing 10, so that the three condenser sections 33, 34 and 35 and the shroud 41 encircle the sealed casing 10. The shroud is provided with a tubular opening 42 in which is disposed a fan 44 connected to a motor 45, driven from a suitable source of power.

Encircling the casing 10, of the compressor-motor unit, is a coil of tubing 46 which is charged with a quantity of fluid capable of absorbing heat. Any suitable refrigerant fluid may be employed, such as sulphur dioxide or even water. The ends 47-47 of the coiled tubing are connected to the headers 48-48 of a secondary condenser 50 disposed across the top of the sealed 10 casing 10 preferably at a slight angle, so that one of the headers 47 will be at a higher elevation than the other. The condenser 50, may be of any preferred construction, but as illustrated, consists of headers 48-48 having a series of tubes 15 51-51 interposed therebetween and connected to the headers for the circulation of the cooling agent. The tubes 51 are provided with fins 52 for dissipating the heat.

The refrigerant or cooling agent contained in 20 the coiled tubing 46 will circulate and be caused to boil within the tubing as the heat is extracted from the sealed casing 10 and motor-compressor units 17-18, and the vapors emanating from the cooling medium will enter the condenser 50 25 through one of the tubes 47, where the vapors will condense and the condensed liquid will return through the other tube 47 from the condenser to the coiled tube 46 for further circulation and cooling. The coiled tube 46 and condenser 50 30 therefore act as a heat exchanger for the sealed casing 10 of the motor-compressor unit in extracting the heat generated during the operation of the unit.

The several units or sections of the condenser 40 29 encompassing three sides of the sealed casing 10, and the fan 44 and shroud 41 at one end thereof, provide an enclosure, so that as the fan 44 is driven, air is drawn through the several condenser sections 33, 34 and 35 around the walls 45 or sides of the sealed casing, and at the same time air is being drawn through the secondary condenser 50 positioned within the area of the condenser 29 and over the top of the sealed casing. Therefore, heat is being extracted from the condensers 29 and 50 and from the top and side walls 50 of the sealed casing 10, at the same time by the suction created by the fan 44 in drawing the air over the sealed casing. Furthermore, the sealed casing is being additionally cooled by the cooling 55 medium of the coiled tubing 46. In this manner heat is being dissipated from the motor-compressor unit and its sealed casing by a compact arrangement of the several condensers, and making it possible to employ such a system in the 60 machine compartment of a domestic refrigerator cabinet.

In Figure 4 is disclosed a condenser which may be employed in lieu of that shown in Figures 1 and 2. This condenser is constructed of a bank 65 of sinuous tubing 55, and adapted to enclose three sides of the sealed casing 10, and may be made U-shaped, or of a configuration to conform to the contour of the sealed casing. The tubing 55 is supported by angle plates 66 located at the corners or at the juncture where the two side walls join the intermediate portion. Fins 57 are provided on the tubing except where the angle plates are attached.

In some instances it may be desired to operate 70 the system without the use of fan 45. This may

be readily accomplished by inserting the condensing unit in the machine compartment of a household refrigerator and providing a flue for inducing a flow of natural air convection currents over the condensing unit and through the flue. In this case it may be desirable to extend the condenser around all four sides of the motor compressor unit instead of only three sides. In this case the four sided condenser may be spaced laterally and vertically from the bottom of the dome so that air may pass upwardly through the condenser and about the dome. A refrigerator cabinet utilizing a flue construction suitable for use in connection with the condensing unit disclosed herein is as disclosed in Patent No. 1,673,- 15 082 to Alfred S. Lewis, patented June 12, 1928.

By providing coils 46 which surround the motor compressor unit a very efficient heat removal arrangement is provided. Coils 46 may be rigidly secured to the compressor dome by fusion, such as welding or soldering. By utilizing the secondary condenser for cooling the compressor, effective cooling takes place and the secondary condenser does not transmit noises from the motor compressor unit as is the case where large 20 heat transfer fins are secured to the motor-compressor dome to dissipate heat from the dome.

Although only a preferred form of the invention has been illustrated and that form described in detail, it will be apparent to those skilled in 30 the art that various modifications may be made therein without departing from the spirit of the invention or from the scope of the appended claims.

What I claim is:

1. Refrigerant apparatus, comprising a sealed 35 casing housing a motor-compressor unit, a condenser for receiving a refrigerant fluid discharged from said compressor, means for containing a cooling fluid associated with said casing 40 in heat exchange relation therewith, and a condenser connected to said means and overlying said casing for radiating the heat absorbed thereby.

2. Refrigerant apparatus, comprising a sealed 45 casing housing a motor-compressor unit, a condenser substantially enclosing the side walls of said sealed casing and connected to the compressor for receiving compressed refrigerant therefrom, means for containing a cooling fluid 50 associated with said casing in heat exchange relation therewith, a condenser connected to said means and overlying said casing for radiating the heat absorbed thereby, and means for drawing air through said condensers and over the walls 55 of said casing for extracting the heat therefrom.

3. Refrigerant apparatus, comprising a sealed 60 casing housing a motor-compressor unit, a condenser substantially enclosing the side walls of said sealed casing and connected to the compressor for receiving compressed refrigerant therefrom, means for containing a cooling fluid 65 associated with said casing in heat exchange relation therewith, a condenser connected to said means and overlying said casing for radiating the heat absorbed thereby, a shroud arranged at a side of said casing and connected to said first mentioned condenser for forming an enclosure for said casing, said shroud having an opening therein, and a power driven fan positioned adjacent 70 said shroud opening for drawing air through said condensers and over the walls and top of said casing for extracting the heat therefrom.

4. Refrigerating apparatus, comprising a sealed 75 casing housing a motor-compressor unit, 75

a condenser encompassing three sides of said sealed casing and for receiving compressed refrigerant from said compressor, a shroud arranged at the remaining side of said casing and 5 connected to the condenser for forming an enclosure for said casing, said shroud having an opening therein, and a power driven fan positioned with respect to the opening of the shroud for drawing air through said condenser and 10 shroud and over the sides of said casing for extracting the heat thereof.

5. Refrigerating apparatus, comprising a casing housing a motor-compressor unit, means for containing a cooling fluid associated with said casing in heat exchange relation therewith, a condenser connected to said means and overlying 5 at least part of said casing for radiating the heat absorbed thereby, and a condenser for receiving fluid discharged from the compressor and positioned along the side wall of said casing.
